UNITED STATES PATENT OFFICE.

MICHAEL B. RYAN, OF BRIDGEPORT, CONNECTICUT.

WIRE CHAIN-LINK.

1,093,209.

Specification of Letters Patent. Patented Apr. 14, 1914.

Application filed November 18, 1911, Serial No. 661,125. Renewed December 20, 1912. Serial No. 737,910.

To all whom it may concern:

Be it known that I, MICHAEL B. RYAN, a citizen of the United States, residing in the city of Bridgeport, county of Fairfield, State of Connecticut, have invented certain new and useful Improvements in Wire Chain-Links; and I do declare the following to be a full, clear, and exact description of the invention, such as will enable others skilled in the art to which it appertains to make and use the same.

My invention relates to certain improvements in wire chain links, and has for its object to form a link from metal so that it will be substantially endless, and at the same time to greatly strengthen the link, and with these ends in view my invention consists in certain methods and details of construction hereinafter fully set forth and then particularly pointed out in the claims which conclude this description.

In the accompanying drawing Figure 1 is an elevation showing a blank with eyes formed at the ends thereof in accordance with my improvement—Fig. 2 is a plan view of a completed link preparatory to the welding operation—Fig. 3 a side elevation of such link—Figs. 4 and 5 are plan views respectively of obverse and reverse faces of a completely welded link, and Fig. 6 an enlarged section at the line x, x , of Fig. 5.

Similar numerals of reference denote like parts in the several figures of the drawing.

In carrying out my improvement I form eyes 1, 2, at the ends of a suitable wire blank 3 by bending the ends in the arc of a circle and in reverse directions. The blank is then bent at its middle portion so as to form a bow 4 and to bring the eyes together so that they will be in a plane at right angles to the plane of the bow. The eyes are then pressed together and welded from the point where one eye joins one side wire 5 of the bow to the point where the other eye joins the other side wire 6 of said bow, this welding being preferably effected without joining the ends of the wire to the body of the wire, the weld being denoted by the numeral 7. This will form a link in which the eyes are welded together from the base portion of the eye 1

where it joins integrally the side wire 6 around throughout the circuit of the eyes to the base portion of the eye 2 where it joins integrally the side wire 5, so that the link will be formed from one substantially endless piece of wire the eye of the link being of double thickness.

A link made as above described is not only exceedingly strong but insures the saving of considerable wire which would otherwise be utilized in anchoring the ends of the eyes to the side wires.

In welding together metal parts great trouble is generally experienced with the bur that is incident to the welding, and the welded articles have to undergo a special treatment such as tumbling in order to remove this bur. In my improvement any undue flow of metal is distributed and taken care of within the space between the outer and inner peripheries of the eyes as is clearly shown at Fig. 6 and it is impossible for any projecting bur to form and therefore no tumbling or other finishing operation is necessary.

It is not necessary, in forming the eyes, to abut the ends of the eyes against the body of the wire, since said ends may be slightly spaced from the wire, it being clear that in both instances after welding the link will be practically formed from an endless wire of double thickness at the eye portion, and in this connection I would say that any joining of these ends to the body of the wire by the operation of welding would be merely incidental.

I do not wish to be understood as claiming the welding of the eye portions of the link together such as could be effected in the instance of eyes which were formed by bending the ends of the blank in the same direction since this would not afford an endless circuit of the wire, neither do I wish to be understood as claiming the manner in which the link itself is formed irrespective of welding. But

What I do claim as new and desire to secure by Letters Patent is:—

1. A chain link comprising a bow portion and two eyes disposed side by side, the metal

forming the eyes extending in opposite directions, and said eyes being welded together.

2. A wire chain link comprising a bow portion and two eyes disposed side by side, the metal forming the eyes extending in opposite directions relatively to each other and in a plane substantially at right angles to the plane of the bow, the said eyes being welded

together throughout substantially their entire circuit to form a substantially integral eye structure. 10

In testimony whereof I affix my signature in presence of two witnesses.

MICHAEL B. RYAN.
